UNITED STATES PATENT OFFICE

BRACE S. KNABENSHUE, OF WARREN, PENNSYLVANIA, ASSIGNOR TO TRAVELERS' LEAGUE, INCORPORATED, OF WARREN, PENNSYLVANIA, A CORPORATION OF DELAWARE

DESIGN FOR A ROAD SIGN

Application filed October 28, 1930. Serial No. 37,409. Term of patent 7 years.

To all whom it may concern:

Be it known that I, BRACE S. KNABENSHUE, a citizen of the United States, residing at Warren, in the county of Warren and State of Pennsylvania, have invented a new, original, and ornamental Design for Road Signs, of which the following is a specification, reference being had to the accompanying drawing, forming part thereof.

The figure is a perspective view of the obverse side of a road sign, of my design the reverse side being plain.

I claim:

The ornamental design for a road sign, as shown and described.

BRACE S. KNABENSHUE.
